ATTORNEY.

UNITED STATES PATENT OFFICE.

HENRY FORD, OF DEARBORN, MICHIGAN.

IGNITION DEVICE.

Application filed October 14, 1926. Serial No. 141,549.

The object of my invention is to provide an ignition device for internal combustion engines, of simple, durable and inexpensive construction.

5 A further object of my invention is to provide an ignition device having associated therewith an automatic spark advancing device, and to provide means for lubricating the moving mechanism of the said spark advancing device.

10 A further object of my invention is to provide an ignition device, such that the operation thereof may be inspected and watched while the internal combustion engine is operated.

15 Still a further object of my invention is to provide a governing device which is lubricated by the lubricating fluid ordinarily used in connection with the crank case of an internal combustion engine, and which may be 20 large enough to insure long life and accurate operation.

25 Still a further object of my invention is to provide a particular type of casing for my improved ignition device, which will insure easy manufacture and accurate operation of the device.

30 With these and other objects in view my invention consists in the arrangement, combination, and construction of the various parts of my improved device, as described in the specification claimed in my claims, and shown in the accompanying drawings in which:

35 Fig. 1 shows a vertical, central, sectional view through my improved ignition device and a partial view of the combustion engine with which it is associated.

Fig. 2 shows a vertical sectional view taken on the line 2—2 of Fig. 1.

40 Fig. 3 shows an end elevation of my improved ignition device, the line 1—1 thereon illustrating the plane through which Fig. 1 is taken.

Fig. 4 shows a transverse vertical sectional view taken on the line 4—4 of Fig. 1.

45 Referring to the accompanying drawings, I have used the reference numeral 10 to indicate the forward portion of the crank case housing provided in connection with an internal combustion engine, this housing having a bearing sleeve 11 formed integrally therewith to support the cam shaft of the internal combustion engine. The bearing sleeve 13 is set into the sleeve 11 to form the actual bearing 50 for the cam shaft 12.

55 The housing 10 has an extension 14 thereon

devised to form the rear portion of the housing for a time gear 15. This time gear in the form of device here illustrated differs from the ordinary timing gear in that it consists 60 of members 16 and 17 designed to have an oil space between them, so that oil from the hollow cam shaft 12 may pass through an outlet 18 from the cam shaft through a groove 19 in the sleeve 13 and thence through an opening 65 20 in a flange on the cam shaft to the interior of the time gear.

It should be suggested that this hollow oil filled time gear is of great advantage in connection with an internal combustion engine 70 as its operation is much quieter than an ordinary solid time gear and in that it forms an oil filled pocket in which the governor mechanism for my spark device may be housed.

The time gear 15 is secured to the cam shaft 75 by bolts 21 which pass through the flange on the cam shaft, which has heretofore been mentioned, and to which I have given reference numeral 22.

The forward end of the cam shaft 12, adjacent to the flange 22 and the time gear 15, is bored out to form a hollow bearing sleeve within which is rotatably mounted the operating shaft 23 of the time drive.

Rotatably mounted on the outside of the 85 cam shaft 12 and within the time gear 15 is a ring 24 which has a pair of oppositely extended arms 25. This ring 24 is provided with a pair of oppositely disposed slots 26 designed to receive the contracted ends of a pin 28 90 which passes through elongated slots 29 in the cam shaft 12 and a corresponding opening in the timer operating shaft 23.

The opening in the ring 24, the cam shaft 12, and the timer operating shaft 23 are such 95 that the ring 24 will rotate with the operating shaft 23, and with limited rotary movement relative to the cam shaft 12, the slots 29 in the cam shaft 12 limiting such movement.

100 A pair of pins 30 extend through a pair of bosses in the member 16 of the time gear and corresponding openings in the member 17 of the time gear to thereby form a pin support for a pair of governor weights 31, 105 which are disposed within the pocket formed in the time gear 15. The pins 30 are provided with an enlarged section between the bosses in the member 16 and the member 17, which prevent longitudinal displacement of these 110 pins. The space between said bosses and the member 17 is such that lateral sway of the

governor weights 31 is limited. A pair of pins 32 are fixed in the time gear member 16 and connect with one end of springs 33 the other end of said springs being connected to 5 suitable pins 34 on the governor weights 31, these springs 33 being adapted to draw the weights 31 on their pivots towards cam shaft 12. Notches 35 are provided in the weights 31 to coat with the ends of the arms 25 on 10 the ring 24.

As the cam shaft 12 is rotated by the internal combustion engine with which it is associated, it will be seen that the governor weights 31 will be carried around by their 15 pivoted connection with the time gear 15 so that the ends thereof, due to centrifugal force, will tend to force away from the cam shaft 12 against the pull of the springs 33 and thereby carry arms 25 on the ring 24 around 20 the cam shaft 12 in the direction of the arrow 36 shown in Fig. 4. This rotation of the arms will in turn rotate the ring 24 and consequently, thru pins 28, the timer operated shaft 23.

25 It will also be seen that the size of these weights 31 can be so proportioned, relative to the ordinary speeds of the cam shaft 12 and the pull of the springs 33, that the position of the timer operated shaft 23 relative to 30 the cam shaft 12 may be regulated by the speed of the cam shaft 12.

The member 16 of time gear 15 is provided with a plurality of studs 37 which extend toward the member 17 of the time gear and 35 form a spacing device for the central portions of these timing gear members. These timing gear members are held in alignment by the pins 30 and prevented from lateral displacement relative to each other by being held between the flange 22 of the cam shaft 40 12 and the bearing sleeve 38 of the engine.

The ignition device proper of my invention is disposed forwardly from covering plate 39 of the engine, so that it may be readily accessible at all times for inspection, adjustment, replacement and repair.

A base member 40, comprising a substantially circular disc, has an annular channel formed adjacent to the periphery thereof and 50 a flange at the periphery thereof. An opening is provided at the center of this base 40 to receive the cam shaft 12. This member 40 fits in a circular opening in the cover plate 39, which is concentric with the cam shaft 12, 55 the channel of the base 40 extending into the cover plate 39 and the flange being adjusted to bear against the surface of the cover plate.

A ring 41 of angular cross section bears 60 against the edges of the channel in the base 40 and coacts therewith to form an annular pocket upon the cam shaft 12, which is designed to receive a condenser unit 42, which 65 may be suitably shaped to fit in this annular pocket.

65 A substantially cylindrical shell 43 of bakel-

ite or other suitable insulating material forms the body of my improved ignition device, and is provided with a plurality of bosses 44 designed to receive sockets 45, and to form the terminals connecting these sockets with the high tension ignition wires 46 in the form of device here shown. These ignition wires are provided with resilient sleeves at the end thereof to frictionally engage the inner surfaces of the sockets 45 fixed in the bosses 44, 70 so that the high tension ignition wires may be readily attached and detached relative to the timing device. It will be understood that there are sufficient of these bosses to provide terminals for each high tension ignition 75 wire necessary for the internal combustion engine and in addition thereto terminals for the high and low tension wires leading to the coil. The high tension coil lead is indicated at 47 and the low tension coil lead is indicated 80 at 48. The reference numeral 48.

The body 43 is provided with an annular flange 49 adjacent to the base 40 and designed to register with a flange on the base 40 so that a plurality of machine screws 50, or other suitable engaging devices may be passed through the flanges of the body and base member into the cover plate 39 to secure the parts of the ignition device together and on to the cover plate of the engine. A lug 51 90 may be turned up from some suitable portion of the flange on the base 40 to coat with a corresponding notch in the body 43 so that the latter may have a relatively fixed position as compared with the engine with which 95 it is associated so that there will be a minimum danger of connecting the high tension wires or the body to the ignition devices in the wrong position to thereby cause improper ignition.

A flat ring or washer 52 is detachably secured to the ring 41 by any suitable means as by screws 53 and provides a removable and adjustable base for the breaker arm of the low tension current circuit.

Elongated openings or slots (53a) in the ring 52 are of such proportions that screws 53 pass thru them and are secured in ring 41. This arrangement allows for a limited rotation of the breaker arm base and provides for an adjustment of the breaker arm with reference to the cam 60 to be described later.

The breaker arm 54 is pivotally mounted on pin 55 which is secured to the base 52 thru an insulating sleeve 55a, and the free end thereof is yielding urged in the direction of a fixed contact member by a leaf spring 56. The fixed contact member comprises a post 57 fixed to the base 52 and provided with a threaded opening designed to adjustably receive the correspondingly threaded contact member 58 which is provided with a lock nut 59 for securing it in an adjusted position.

The timer operating shaft 23 is provided with a sleeve member 62 mounted on its outer end which has a plurality of substantially flat surfaces 60 in vertical alignment with breaker arm 54, so that this flattened portions of the sleeve 62 may form a multiple cam member designed to operate the breaker arm 54 when the shaft 23 is rotated to intermittently break the contact between the breaker arm 54 and the fixed member 58.

The breaker arm 54 is provided with an insulating lug 61 designed to contact with the cam 60. In the form of device here illustrated the breaker arm 54 and spring 56 are designed to be connected with the low tension side of the ignition coil and the stop or contact 58 grounds the circuit from the coil when the breaker arm 54 is permitted to be in contact therewith, by the cam 60.

The form of adjustment for the cam 60 consists of loosely mounting the sleeve 62 on the operating shaft 23, the latter being provided with a split end portion which receives a tapered screw indicated by the dotted line 63 so that the position of the cam faces 60 may be adjusted relative to the timer shaft 23 by rotating thereon sleeve 62 and then locking same in position by screwing down screw 63.

The sleeve 62 is provided with a contracted end portion 64 having a flat side which is designed to extend into a mounting sleeve 65 extending from the distributor arm 66. The body of the distributor arm is moulded from insulating material and is provided with a strip of conducting material 67, which is preferably secured to the body of the distributor arm 66 by being moulded therein.

It will be seen that the distributor parts just described, will rotate with the timer shaft 23 and it will be noted that the strip 67 is so mounted on the distributor arm that it extends to position from approximately the center of the cam shaft 12 to the contacts 45.

The terminal for the high tension lead wire 47 is provided with a bolt 68 whereby a bracket 69 having a pair of ears extending therefrom may be secured to the inner wall of the body 43 in position out of the path of travel of the distributor arm 46. A spring contacting member 70 is pivotally mounted in the ears of the bracket 69 and extends to a position adjacent to the center of the cam shaft 12 and the inner end of the strip 67 of the distributor arm 66. This free end of the contact member 70 is yieldingly urged by the spring 71 against this strip 67 so that as the shaft 23 and the distributor arm 66 rotate a circuit contact from the wire 47 thru the contact member 70 and distributor arm 66 may be completed to the high tension lead wires 46 and thence to the engine. This spring contact member 70 performs a dual function of holding distributor arm 66 in place on the shaft 23 and of carrying current

from the spark coil to the distributor arm. It will be noted that the position of the distributor arm relative to the cam faces 60 is fixed by the flattened side of the forward portion of the sleeve 62, which fits into a correspondingly shaped opening in the boss 65 of the distributor arm 66. A closure member 72, which is preferably formed of insulating material, is removably secured to the body 43 by a leaf spring 73 which yieldingly urges the closing member 72 against the body member 43. This spring 73 operates from the cover plate 49 in any suitable manner, as by being mounted on a stud 74 which extends through the flanges of the body 43, and base 40 and is secured in the cover member 39.

The condenser 42 is connected across the breaker arm 54 and the fixed contact 58, in order to lessen the wear on the contact points due to sparking. The connections for this circuit are not here illustrated as they are common to practically all internal combustion engines now made, and form no part of my invention except as associated with the form of device herein disclosed.

In the practical operation of my improved ignition device it will be seen that the parts may be assembled as illustrated in Fig. 1 and the sleeve 62 adjusted so that the distributor arm will direct current to the proper socket 95 and wire thru the full advancing range, the breaker arm being adjusted in reference to cam 60, by rotating the base plate 52 so that a break will be caused in the low tension circuit at the proper time for the engine upon 100 which this ignition device is installed. After the engine is started it will be seen that the time gear will be rotated and consequently the governor weights will be swung out relative to the shaft 12 in the manner heretofore 105 described to thereby correspondingly vary the position to the cam 60 relative to the cam shaft 12. This variation in position is such that the spark will thereby be automatically advanced so as to occur at the proper instant 110 at all engine speeds for the proper ignition of the engine. The principals governing the adjustment of these cams and of the automatic spark for automobile combustion engines are generally understood and the exact 115 direction for such adjustments need not here be given.

Among the many advantages arising from my improved ignition device it should be first pointed out that I have a spark control 120 device which is mounted in such a position that it is lubricated by the crank case oil of the engine and lubrication thereto could be said to be automatic. Further this automatic controlling device is mounted in such position, namely in the time gear of the engine, that it does not take up any extra room in the engine and at the same time it may be made large enough to be relatively highly efficient. In fact this position of the governing 125

devices in the engine and the time gear of the engine is of such an advantage that I have not found it necessary to provide the spark manual control ordinarily provided in addition to the automatic spark control.

A further advantageous result of my improvement is that I am able to remove the enclosure member 72 and thereby inspect any of the current carrying members of my ignition device without changing their position or affecting the operation of the ignition devices. This enables me to watch the spark between the distributor arm and high tension contact points, when the engine is running at any speed, to determine whether all of the cylinders are being fired, and as to which one is not being fired if any.

A further advantage resulting from the use of my improved device is that I am enabled to adjust the distributor arm for firing the correct cylinder and also to direct the spark to said cylinder thru the full advancing range, the actual spark timing being done by rotating the breaker arm base plate.

Still a further advantage results from the fact that I am enabled by removing the distributor arm 66 to adjust the cam 60 relative to the shaft 23 and that this adjustment is facilitated because the cam may be locked in any desired position by locking down screw 63.

Some changes may be made in the arrangement, construction and combination of the various parts of my improved device without

departure from the spirit of my invention and it is my intention to cover by the following claims such changes as may reasonably be included within the scope thereof.

I claim as my invention:

1. A combination with an internal combustion engine having a housing and cam shaft, 40 a hollow timing gear mounted on the cam shaft, and an ignition device comprising an operating shaft, automatic advancing means for said operating shaft being mounted within said time gear and designed to vary the position of said operating shaft, and a circuit making and breaking device mounted outside the said housing in position to be operated by said operating shaft.

2. In an electrical ignition device for internal combustion engines the combination with an engine of a housing and cam shaft and hollow timing gear mounted on the cam shaft with a governing device comprising a member mounted in said timing gear and adapted to be responsive to centrifugal force, an operating shaft rotatably mounted in said cam shaft, and means for operatively connecting said operative shaft with said member whereby centrifugal force may automatically cause 55 movement of the operating shaft relative to the cam shaft.

Signed at Dearborn, in the county of Wayne, State of Michigan, this 24th day of September, 1926.

HENRY FORD.
